SAFETY HEADLIGHT REFLECTOR

Richard G. Harris, Knoxville, Tenn.

Application April 23, 1935, Serial No. 17,861

1 Claim. (Cl. 240—41.2)

The invention relates to a headlight and more especially to a vehicle lamp for locomotives, street cars, buses, boats or the like.

The primary object of the invention is the provision of a lamp of this character, wherein through the use of a reflector and an electric bulb light rays will be projected for the purpose of lighting up a straight course or curves to either side of this course and in this manner there will be avoided headon or rear end collisions with vehicles, the lamp throwing light so as to provide for roads leading off from either side of a straight course as well as throwing the light on ditches or other obstructions and enabling an operator of the vehicle to have clear vision of a person or persons standing at a curve or a sidewalk and thus being able to avoid accidents and injury to such person or persons.

Another object of the invention is the provision of a lamp of this character, wherein the reflector employed is of novel construction in that rays of light issued from a bulb will be directed to the right and to the left with respect to a person seated in a vehicle as one beam of light will have its focal axis at an angle to the focal axis of the reflector and thus a straight light beam will be issued from the lamp and angular light beams to either side of the straight beam, the bulb employed in the lamp being also of novel construction.

A further object of the invention is the provision of a lamp of this character, which is extremely simple in its construction, thoroughly reliable and efficient in its purposes, possesses but few parts assembled in a novel manner and certain of these parts being of novel construction, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a horizontal sectional view through a lamp constructed in accordance with the invention.

Figure 2 is a front elevation of the reflector.

Figure 3 is a sectional view on the line 3—3 of Figure 2 looking in the direction of the arrows.

Similar reference characters indicate corresponding parts throughout the several views in the drawing.

Referring to the drawing in detail, A designates generally a portion of a lamp housing or

casing having at its front a removable lens or glass 5 which is held in place in a conventional manner with respect to the casing A. In rear of the lens or glass 5 and within the housing or casing A is a reflector 6 which may be of any suitable curvature to normally focus the rays of light from a centrally located lamp so that the rays of light are projected forwardly in substantial parallelism.

This lamp 7 is an electric bulb and is of T-shape with the ends 8 of its cross head disposed in a rearwardly diverging relation to each other and protrude into facets or depressions 9 provided in the main reflector 6. This bulb when electrically lighted will effect the issuance of rays of light at opposite sides of a central focal point angularly both to the right and left of the forwardly directed light. In other words, a light beam will be disposed at the focal axis of the reflector and supplemental thereto will be angularly disposed beams of light to opposite sides of the focal axis so that light will be cast or thrown to either side and in the direction of a forward straight course, there being employed but a single bulb for this purpose.

In the illumination of the lamp an operator of a vehicle using the latter will have clear view of everything in front of such vehicle and particularly roads leading off to either side of the straight path of travel of such vehicle, the lamp being a safety device to avoid collisions and injury to pedestrians. The disposition and the nature of the facets or depressions are such as to have the axis of the light beams properly disposed so as not to approach pedestrians or traffic.

Carried by the lamp housing or casing A is a park light bulb 10 it being projected through a suitable opening in the reflector at the desired point of the same and such bulb 10 is utilized only for parking purposes.

The reflector 6 is preferably made from blown glass although it can be molded of brass, the glass being nickled on the outside with the bulb 9 placed internally.

What is claimed is:

A light projector comprising a reflector having an axial central socket and a pair of rearwardly projecting depressions, one on each side of the socket, which present an unbroken reflective surface, and a T-shaped bulb having the base thereof mounted in the socket and the outer ends thereof rounded and placed centrally in said depressions, and three light sources within said bulb positioned respectively in the focus of the reflector and in the rounded ends of the T-shaped bulb.

RICHARD G. HARRIS.
